UNITED STATES PATENT OFFICE.

WILLIAM YAKISH, OF MADISONVILLE, TEXAS.

DESIGN FOR A CURTAIN-HANGER.

51,944.

Specification for Design.

Patented Apr. 2, 1918.

Application filed August 17, 1917. Serial No. 186,811. Term of patent 7 years.

To all whom it may concern:

Be it known that I, WILLIAM YAKISH, a citizen of the United States, residing at Madisonville, in the county of Madison and State of Texas, have invented a new, original, and ornamental Design for Curtain-Hangers, of which the following is a specification, reference being had to the accompanying drawing, forming a part thereof.

Figure 1 is a front elevation of a curtain hanger, showing my new design;

Fig. 2 is a side elevation; and

Fig. 3 is a top plan view.

I claim:

The ornamental design for a curtain hanger, as shown.

WILLIAM YAKISH.

Witnesses:

A. P. JENKINS,
J. T. LONGBOTHAM.
